UNITED STATES PATENT OFFICE

94,323

DESIGN FOR A JIG-SAW PUZZLE

Howard A. Baltzer, Hamburg, N. Y.

Application August 24, 1934, Serial No. 53,036

Term of patent 7 years

To all whom it may concern:

Be it known that I, Howard A. Baltzer, a citizen of the United States, residing at Hamburg, Erie

County, State of New York, have invented a new, original, and ornamental Design for a Jig-Saw

Puzzle, of which the following is a specification, reference being had to the accompanying drawing, forming a part thereof.

The figure is a perspective view of a jig-saw puzzle embodying my new design.

In the design, the figure is releasably confined to the wall by a suitable connection with it, and the wall and figure thus constitute a single unitary design.

I claim:

The ornamental design for a jig-saw puzzle substantially as shown and described.

HOWARD A. BALTZER.
